OTTO SINDL, OF MAHRISCH CROSTAU, CZECHOSLOVAKIA.

ALTERNATING-CURRENT CENTRIFUGE.

Application filed September 2, 1924. Serial No. 735,445.

- It is well known that the problem of making centrifugal machines run quietly and without jarring or bumping presents great difficulties, since the high circumferential velocity required in order to obtain a satisfactory centrifugal action results in producing jars of considerable force, with consequent danger of breakage when slight deviations from equilibrium occur in the machine.
- In order to overcome this defect, it has been proposed to mount the spindle and basket of the machine for free movement; but such arrangement, however, according to the present methods of construction, can be carried out in practice to a limited extent only, because the driving element or motor has the effect of setting up additional forces which interfere with the centrifugal motion.
- In centrifugal machines provided with direct electric drives, to which the present invention relates, the entire driving motor usually has to be suspended in such a way as to permit it to oscillate, whence it follows that if the basket or the spindle is caused to swing owing to a want of balance, the non-rotating parts such as the stator, bearings and the like, must also participate in this motion, which results in preventing the full centrifugal action from being obtained. In consequence, it is virtually impossible to run the machine entirely without jarring.
- The object of my invention is to produce an electrically-driven centrifugal machine in which these objections are overcome, two forms of such a machine being illustrated in vertical section in Figures 1 and 2 of the accompanying drawing.
- In Fig. 1, T represents the centrifugal basket which is mounted in and fastened to the supporter K, the latter being fitted with the laminated iron core R of the rotor, and with the squirrel-cage winding and the bars A. The spindle N is mounted at its lower end in a ball-bearing which may be of the well-known SKF type and which is sup-
- ported by a case G. Connected with the case G is a plate P which carries the stator core S in the grooves of which the windings W are inserted.
- The confronting faces of the stator and the rotor are spherically turned, so that in case the spindle swings laterally in any direction no contact can take place. To prevent the basket, when at rest, from overturning, springs F are placed in the frame or case G which exert a slight supporting action on the spindle so as to maintain it in its central position.
- Fig. 2 shows an analogous device in which, however, the basket and rotor are connected by a short spindle. The whole is so arranged that the center of gravity lies beneath the supporting bearing, wherefore the supporting springs F may be omitted.
- I claim as my invention:
- Mechanism for rotating a relatively-large body at high speed, involving a spindle to which such body is directly affixed, a supporting frame, a ball-bearing wherein the spindle is mounted located in said frame and providing a center of oscillation about which said spindle tilts consequent upon the centrifugal forces exerted on said body incidental to its rotation, and a motor for driving said spindle located at a point remote from said ball-bearing; said motor comprising a rotor fastened immediately to the spindle and a stator fastened immediately to the frame, the rotor and stator constituting companion parts, one of which has a convex face and the other a concave face to conformably receive said convex face, the center of curvature of both faces being the aforesaid center of oscillation of the spindle, whereby said faces are constantly maintained in spaced, parallel relation throughout their entire extent during the tilting movements of the spindle.

In testimony whereof I affix my signature.

OTTO SINDL.
